DOUBLE ACTING PUMP CYLINDER

Filed March 27, 1929

UNITED STATES PATENT OFFICE

ARNOLD BOHNENBLUST, OF RILEY, KANSAS

DOUBLE ACTING PUMP CYLINDER

Application filed March 27, 1929. Serial No. 350,215.

This invention aims to provide a very compact pump which will raise a large amount of water with a minimum length of stroke.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the drawing the invention is shown in a single figure which is a vertical longitudinal section.

The pump forming the subject matter of this application comprises a cylinder C, including an upper member 1, and a lower member 2 having an inlet 3 at its lower end. The letter B designates a barrel comprising a lower part 4 supported in the lower member 2 of the cylinder C, and an upper part or pipe 5 supported in the upper member 1 of the cylinder C.

A partition P separates the upper member 1 of the cylinder C from the lower member 2 of the cylinder, and the partition P separates the upper member 1 of the cylinder C from the lower part 4 of the barrel B. The partition P has ports 6 establishing communication between the lower part 4 of the barrel B and the upper member 1 of the cylinder C. The port 6 is controlled by a downwardly closing first check valve 7. A downwardly closing second check valve 8 controls the passage of liquid from the inlet 3 to the lower end of the lower part 4 of the barrel B. A downwardly closing third check valve 9 controls the passage of liquid from the inlet 3

to the lower end of the lower member 2 of the cylinder C.

A hollow piston rod 10 is mounted to slide through the partition P, and it communicates at its lower end with the lower part 4 of the barrel B between the partition P and the second check valve 8. A downwardly closing fourth check valve 11 is carried by the lower end of the piston rod 10, and controls the passage of liquid through the piston rod. A bottom piston 12 is mounted on the rod 10 and slides in the lower part 4 of the barrel B between the partition P and the second check valve 8. A top piston 14 is secured to the rod 10 and operates in the upper part 5 of the barrel B. Ports 15 in the upper end of the lower part 4 of the barrel B constitute means for establishing communication between the upper end of the lower member 2 of the cylinder C and the upper end of the lower part 4 of the barrel B.

Ports 16 constitute means for establishing communication between the upper part 5 of the barrel B and the interior of the hollow piston rod 10 at a point above the top piston 14.

On the down stroke of the piston rod 10, the second valve 8 closes, the fourth valve 11 opens, liquid passes out through the ports 16, into the space within the upper part 5 of the barrel B, above the top piston 14. As the bottom piston 12 moves downwardly, the first valve 7 closes, liquid is sucked through the ports 15 into the space within the lower part 4 of the barrel B, above the bottom piston 12, and the suction thus created in the lower member 2 of the cylinder C causes the third check valve 9 to open and admit liquid to the lower member 2 of the cylinder C from the inlet 3.

On the up stroke of the piston rod 10, the third check valve 9 is in closed position. The second check valve 8 is in open position. The fourth check valve 11 is in closed position. The first check valve 7 is in open posi-

tion. The bottom piston 12 sucks the liquid from the inlet 3 into the lower end of the lower part 4 of the barrel B. Because the fourth check valve 11 is closed, the liquid 5 inside of the hollow piston rod 10 is raised. The liquid in the upper part 5 of the barrel B, above the top piston 14, is raised. The bottom piston 12 raises the liquid in the upper end of the lower part 4 of the barrel B, 10 through the ports 6 past the first valve 7, and upwardly in the upper member 1 of the cylinder C.

Passing to a more detailed description of the invention, the lower part 2 of the cylinder 15 C is threaded into a base 17, having an internal shoulder 18, and the inlet 3 being mounted in the lower end of the base 17.

A valve cage is provided and includes a cap 19, provided at its top with a threaded 20 opening 20. Into the lower end of the opening 20, the upper end of a nipple 21 is threaded. The nipple 21 is provided with an outstanding flange 22. Between the flange 22 and the lower end of the cap 19, a packing 23 is bound. This packing 23 fits closely within the lower part 4 of the barrel B and prevents the liquid from leaking downwardly on to the part 4 of the barrel B around the cap 19. The third check valve 9 slides up and 30 down on the nipple 21 and rests on an upper plate 24 threaded on the lower part of the nipple 21, a lower plate 25 being threaded on the nipple and resting on the shoulder 18. Between the plates 24 and 25 is bound a packing 35 26 that engages the base 17 to prevent leakage. The liquid finds its way upwardly through ports 27 in the plates 24 and 25, and in the packing 26. The ports 27 are controlled by the downwardly closing third 40 check valve 9. The downwardly closing second check valve 8 operates within the cap 19 and may be hinged at 28 to the upper end of the nipple 21, the construction being such that the valve 8 will not close the hole 20, 45 when the valve 8 opens upwardly.

The bottom piston 12 is a composite structure. It includes a hollow foot 29, threaded on the lower end of the rod 10, and a depending neck 30. The neck 30 can be threaded 50 into the opening 20, and in this way, the entire lower valve structure can be lifted out, upon occasion. The fourth check valve 11 may be hinged at 31 within the foot 29 of the bottom piston 12. A disk 32 is threaded on 55 the neck 30, and a packing 33 is bound between the disk 32 and the lower surface of the foot 29, the packing cooperating with the lower part 4 of the barrel B. In this connection it may be stated that the showing of the packings, generally, is simple and more or less diagrammatic, the builder being left 60 to pick out the particular kind of packing that he wishes to use.

The partition P includes a coupling 34 that 65 is threaded into the upper end of the lower

member 2 of the barrel B, the coupling having a depending apron 35 into which the upper end of the lower part 4 of the barrel B is threaded. The ports 15 are located partly in the apron 35, and partly in the upper end 70 of the part 4 of the barrel B. A short nipple 36 is threaded into the lower end of the upper part 5 of the barrel, and it is on this nipple 36 that the first check valve 7 slides. A lower plate 37 is seated in the coupling 34 and is 75 threaded on the nipple 36. An upper plate 38 is threaded on the nipple 36. A packing 39 is bound between the plates 37 and 38, and has a water-tight peripheral contact with the coupling 34.

The ports 6 are located in the plates 37 and 38 and in the packing 39.

The hollow piston rod 10 comprises parts joined together by a coupling 40, the ports 16 being located in the coupling. The disclosure has been confined strictly to the pumping mechanism, and no attempt has been made to show the driving means, including the ordinary solid operating rod, connected to the hollow piston rod 10 and closing it a short distance above the upper end of the part 10 in the drawing, whereby, on the down stroke, as the valve 11 opens, the liquid above the valve 8 will flow upwardly 95 through the hollow rod 10, out of the ports 16, and into the space within the pipe 5, above the top piston 14.

The operation of the device has been dealt with hereinbefore, and the specific structural features alluded to, cause the device to be inexpensive to manufacture, and well adapted to withstand long continued use without much attention.

What is claimed is:—

A pump comprising an upper tubular 105 member, a lower tubular member having an inlet, a lower barrel in the lower tubular member, a removable partition separating the tubular members from each other, and separating the upper tubular member from the lower barrel, the partition being fixedly seated during the operation of the pump, a check valve on the partition, a second check valve structure in the lower barrel, a third check valve structure in the inlet and connected to the second check valve structure, a hollow piston rod slidable in the partition, a piston on the piston rod and slidable in the lower barrel, between the partition and the second check valve structure, interengageable elements on the piston and on the second check valve structure, whereby the second check valve structure and the third check valve structure may be pulled out together, the piston being engaged with said removable but fixedly seated partition to remove the partition at the same time, a fourth check valve carried by the piston, means for establishing communication between the lower tubular member and the lower barrel 110 115 120 125 130

at a point above the piston, weight means
for holding the partition fixedly but remov-
ably seated during the operation of the pump,
as aforesaid, said weight means comprising
5 a pipe surrounding the piston rod and con-
nected to the partition, the piston rod having
an opening establishing communication be-
tween the interior of the piston rod and the
interior of the pipe, and a second piston car-
ried by the piston rod and operating in the
10 pipe, below the opening.

In testimony that I claim the foregoing as
my own, I have hereto affixed my signature.

ARNOLD BOHNENBLUST.
